UNITED STATES PATENT OFFICE.

JOHN B. FREYSINGER, OF NEW BRITAIN, CONNECTICUT.

FLEXIBLE CLOSURE.

Application filed June 24, 1926. Serial No. 118,314.

This invention relates to flexible closures of the type having a pair of stringers or tapes provided on their opposed edges with clasps or locking members which are adapted to be successively brought into interlocking relation when a slide is moved longitudinally of the tapes in one direction and which are disengaged when the slide is moved in the opposite direction.

The object of the invention is to provide a closure of this sort having various features of novelty and advantage, and which is particularly characterized by its economy in manufacture and effectiveness in operation.

A further object of the invention is to provide a flexible closure of this sort having interlocking members which may be economically manufactured, which are relatively strong and durable so that they are enabled to stand the strains and stresses to which they are subjected, which effectively interlock with one another, and which will move through the slide with a very smooth and easy movement, sticking and jamming being avoided.

A further object of the invention is to provide an improved bottom stop for the slide, this bottom stop being of such construction that it may be cheaply made and easily applied.

Another aim of the invention is to provide top stops of improved construction for effectively limiting the closing movement of the slide.

Other objects will be in part obvious and in part pointed out more in detail hereinafter.

The invention accordingly consists in the features of construction, combination of elements and arrangement of parts which will be exemplified in the construction hereinafter set forth, and the scope of the application of which will be indicated in the appended claims.

In the accompanying drawings, wherein I have shown, for illustrative purposes, one embodiment which the present invention may take:

Figure 1 is an elevational view showing the complete assembly;

Fig. 2 is a sectional view taken on line 2-2 and looking in the direction of the arrows associated with that line;

Fig. 3 is a perspective view of one of the locking members;

Fig. 4 is a perspective view of a locking member in inverted position;

Fig. 5 is a development of a pierced blank from which the locking member may be formed;

Fig. 6 is a perspective view of one of the top stops;

Fig. 7 is a perspective view of one of the parts of the bottom stop;

Fig. 8 is a perspective view of the other part of the bottom stop; and

Fig. 9 is a top or edge view of the assembled bottom stop, the flexible stringers or tapes being shown in transverse section.

Referring to the drawings in detail, *a* and *b* denote the respective stringers or tapes; *c*, *c* designate the locking members of the series secured to the tape *a*; and *d*, *d* designate the locking members of the series secured to the edge of the stringer *b*. *e* is a slide for engaging and disengaging the locking members. This slide may be of any suitable construction. *f* designates, generally, the bottom stop, the detailed construction of which will be described hereinafter more in detail. *g*, *g* designate the top stops which will be described later in greater detail.

In the present illustrative disclosure of the invention, the locking members of both series are preferably of identical construction so as to effect economy in manufacture, and each locking member is adapted to be interlocked with a superimposed locking member and the subjacent locking member of the opposite series. Referring more specifically to the locking members, each of these is preferably composed of a strip of sheet metal or other suitable malleable material which is folded over upon itself, each locking member having, adjacent one end, means for securing the same to the tape or stringer and, adjacent its other or free end, a projecting lug or finger, an opening adapted to receive one of these lugs or fingers, and a cam surface whereby the members may ride into proper interlocking relation to each other as they pass through the slide.

In the present illustrative disclosure, the folded over end of the locking member is attached to the tape or fabric but, obviously, the construction may be such that the folded over end may constitute the free end of the locking member. Each of the locking members may be formed by stamping out a pierced blank, such as shown in Fig.

5. This blank has, at one end, a projecting lug or finger 10 and, adjacent to, but spaced from, its opposite end, an opening 11. The blank has a pair of oval openings 13 connected by a longitudinally extending narrow slot 14. The lug 10 is turned down at an angle to the plane of the blank, and the blank is turned over upon itself along the line 15 so as to bring the openings 13 into registry, as shown most clearly in Figs. 3 and 4. The end of the blank beyond the opening 11 is curved or bent downwardly so as to provide a camming surface 16.

To secure the locking members in place, 15 the beads of the stringers are inserted through the openings 13, and then the metal to each side of these openings is forced together. In operation, the lug or finger 10 of each locking member is adapted to engage 20 in the opening or pocket 11 of the next subjacent locking member. When the locking members are moved into and out of locking relation as they pass through the slide, the ends of the lugs are adapted to ride on the 25 camming surfaces 16, as shown most clearly in Fig. 1. It will be noted that the rear or attached ends of the locking members are curved in the plane of the slide so that, as the locking members pass through the slide, 30 there is no danger of them catching or dragging to too great an extent against the outer edges of the passages in the slide. The locking members may be very economically manufactured while, at the same time, they can 35 be uniformly made and they are relatively strong and durable.

In accordance with the present invention, 40 the bottom stop *f* for limiting the opening movement of the slide *e* comprises two members, one of which may be in the form of an apertured plate 25, as shown in Fig. 8. The other part of this stop may be in the form of a plate or flange 26 having a tubular portion 27. The ends of the plates 25 and 26 45 are curved or bent, as clearly shown in Fig. 9. The member having the flange 26 and the tubular portion 27 may be readily, rapidly and cheaply made of sheet metal on the well known and so-called eyelet machine. 50 To assemble the parts, the plates 25 and 26 are positioned so that the beads of the flexible stringers engage between the opposite ends of these plates with the tubular portion extending through the aperture in the plate 25. The end of the tubular portion is 55 then spun or curled over as at 27 so as to securely clamp the two parts to the beaded edges of the tapes or stringers.

Referring now to the top stops, each of 60 these may comprise a strip stamped from sheet metal and folded over upon itself, as shown most clearly in Fig. 6. The blank is pierced with openings 30 and a connecting slot 31 in the same manner as is the blank 65 for forming the locking members. When

the blank is folded over on itself, the openings 30 are in registry and adapted to receive the bead of the stringer. The rear or attached end of the stop *g* is curved, thus providing a rounded cam surface 32 and, if 70 desired, the forward or free end of the stop may be curved or rounded as at 33. Obviously, the flexible closure may have either one or two of these stops, as desired. The slide, as shown in Fig. 1, has a flaring mouth 75 or entrance at the top of the passages therethrough. In the present instance, the upper end of the passage, into which the locking members pass when the slide is moved upwardly, has its outer edge wall inclined as at 80 34 so as to form a cam surface against which the cam surface 32 of the stop is adapted to engage when the slide is moved to its uppermost position. Thus, when the slide is moved to the limit of its closing movement, 85 the cam surface 32 will engage the cam surface 34 and result in wedging the stop in the mouth or entrance of the passage through the slide.

As many changes could be made in the 90 above construction and many apparently widely different embodiments of this invention could be made without departing from the scope thereof, it is intended that all matter contained in the above description or 95 shown in the accompanying drawing shall be interpreted as illustrative and not in a limiting sense.

It is also to be understood that the language used in the following claims is intended 100 to cover all of the generic and specific features of the invention herein described and all statements of the scope of the invention which, as a matter of language, might be said to fall therebetween. 105

I claim as my invention:

1. A locking member for a flexible closure of the character described comprising a strip of material folded over upon itself and with the plies in contact, said member having 110 at one end means for securing the same to a flexible tape and at its other end a depending lug adapted to engage in a pocket in a subjacent locking member and also having a pocket adapted to receive a lug on a superimposed locking member. 115

2. A locking member for a flexible closure of the character described comprising a strip of material folded over upon itself and with the plies in contact, said member having adjacent one end a pair of registering openings adapted to receive the bead of a tape and a slot leading from said openings to the end of said locking member, said locking member having adjacent its other end an 120 opening in one thickness of the member and also having adjacent this latter end a depending integral lug. 125

3. A locking member for a flexible closure of the character described comprising a strip 130

of material folded over upon itself with the plies in contact and one end of the strip overlapping the other end, the upper ply of said member having an opening adjacent its outer end and the under ply having a depending lug, the overhanging end of the upper ply being curved downwardly to provide a camming surface.

4. A locking member for a flexible closure of the character described comprising a strip of material folded over upon itself and with the plies in contact, said member having at its folded over end means for securing the same to a tape, one ply of said member extending beyond the other ply and being turned down over the end edge of the shorter ply, the end edge of the shorter ply having a depending lug and the upper ply having an opening.

5. A flexible closure of the character described having a pair of flexible stringers and a series of locking members on each stringer, said locking members being staggeredly arranged and each comprising a strip of material folded over upon itself and with the plies in contact, the folded over end of each locking member having means for securing the same to a stringer and each locking member having at its opposite end a depending lug and a pocket.

6. A flexible closure of the character described having a pair of flexible stringers, series of locking members carried by said stringers, a slide movable along said stringers to effect engagement and disengagement of said locking members, and a top stop to limit the closing movement of said slide, said top stop comprising a strip of sheet

metal folded over upon itself, said stop having at its folded over end an opening adapted to receive the bead of a stringer.

7. A flexible closure of the character described having a pair of flexible stringers, series of locking members carried by said stringers, a slide movable along said stringers to effect engagement and disengagement of said locking members, and a top stop to limit the closing movement of said slide, said top stop comprising a strip of sheet metal folded over upon itself, said stop having at its folded over end an opening adapted to receive the bead of a stringer, said slide having an inclined camming surface at the upper end and on the outer edge of the passage through which the locking members are adapted to pass when the slide is moved, said camming surface being adapted to be engaged with the folded end of said stop to limit the closing movement of said slide.

8. A flexible closure of the character described having a pair of flexible stringers, series of locking members carried by said stringers, a slide movable along the stringers to effect engagement and disengagement of said locking members, and a stop to limit the opening movement of said slide, said stop comprising a plate having an aperture and a plate having an integral tubular portion adapted to engage in said aperture, the end of said tubular portion being turned over to secure the parts together and the ends of said plates being curved towards each other so as to grip the beads of the stringers therebetween.

JOHN B. FREYSINGER.
